HOWARD E. WHITE, OF HOLDENVILLE, OKLAHOMA, ASSIGNOR OF ONE-HALF TO
HARRY R. ALLEN, OF HOLDENVILLE, OKLAHOMA

JACK TOOL

Application filed September 10, 1928. Serial No. 304,963.

The present invention relates to improvements in special tools and has reference more particularly to a jack tool for positioning girts such as are used in conjunction with the derrick structure embodied in my co-pending application.

One of the important objects of the present invention is to provide a jack tool which will greatly facilitate the positioning of the girts on the derrick, so that the sections of the derrick will be properly supported during the assembly and construction of the derrick.

Still a further object is to provide a jack tool of the above mentioned character that will, at all times, be efficient and reliable in its operation, the same being further simple in construction, inexpensive, strong and durable, and further well adapted to the purpose for which it is designed.

Other objects of the invention will become apparent during the course of the following detailed description.

In the accompanying drawings, forming a part of this application, and wherein like reference characters designate like parts throughout the several views:

Figure 1 is a side elevation of the jack tool embodying my invention, showing the same in the act of positioning a girt.

Figure 2 is a top plan view thereof.

Figure 3 is a detail perspective view of the hooked bar member forming a salient part of the present invention, and

Figure 4 is a detail perspective view of the stud engaging finger.

In the drawings, wherein for the purpose of illustration is shown the preferred embodiment of my invention, the numeral 1 designates the angle iron girt, the specific construction of which is disclosed in my co-pending application and this girt is adapted to span the splice bar units 2 carried by the upper ends of the sections 3 of the adjacent corner posts, also more specifically described in my co-pending application.

As clearly shown and described in my aforesaid co-pending application, a pair of spaced fastening elements 4 and 5 respectively are associated with each splice bar unit, between which fastening elements is adapted

to be disposed the fingers 6, formed at the respective ends of the vertical walls of the angle iron girt 1.

In order to facilitate the installation of these girts during the construction of my derrick, it is necessary to employ a special tool, and to this end the jack tool which I use is shown generally at 7.

This tool comprises an elongated lever 8, the lower end of which is forked, as shown at 9, with reference more particularly to Figure 2. A spindle 10 extends laterally from the lever 8 at a point above the fork 9 for receiving the looped inner end portion 11 of an elongated flat bar 12, whereby said bar member is pivotally associated with the spindle 10. Any appropriate means may be provided on the outer end of the spindle to prevent the casual displacement of the looped inner end 11 of the bar member therefrom.

As clearly shown in Figure 3, the outer free end of the bar member 12 is bent back upon itself to form a hook 13 that is adapted to engage over the right hand end of the horizontal portion of the angle iron girt 1, the bar 12 being adapted to be disposed across the upper face of the horizontal portion of this end of the girt.

A lip 14 extends downwardly from the outer side edge of the bar 12 adjacent the hook 13 for engagement with the adjacent edge of the horizontal portion of the girt 1, in the manner as shown in Figure 1. The lever 8 is disposed adjacent the vertical wall of the girt for disposition inside of the frame structure of the derrick, and pivotally mounted on a pintle 15, that extends transversely across the fork 9 is the inner end of a bar like finger 16, the outer end thereof being formed with a notch 17, as clearly illustrated in Figure 4, for engagement over the adjacent fastening element 4 as shown in Figures 1 and 2.

In use, the left hand end of the girt has its finger positioned between the fastening elements associated with the adjacent splice bar unit while the right hand end portion of the girt assumes the position shown in Figure 1. The jack tool is then placed in position, so that the downwardly curved fork

end 9 of the lever 8 extends alongside of the vertical wall of the girt. The bar 12 is positioned across the upper face of the right hand end portion of the horizontal wall of the girt with the hooks 13 engaging over the outer end of the girt. The notched finger is then brought into engagement with the fastening element 4, and manifestly by swinging the lever 8 downwardly, the spindle 10 will force the right hand end portion of the girt 1 downwardly so that the finger at the right hand end of the girt will be properly positioned between the adjacent fastening elements 4 and 5 of the right hand splice bar unit. After the girt has been properly positioned, the jack tool can be readily and easily removed, and when all of the girts associated with one section of the derrick have been properly positioned, the superjacent section of the derrick may be built up in the manner as also defined in my co-pending application.

It will thus be seen from the foregoing description that I have provided a particular tool for use in conjunction with the assembling of my improved derrick construction which will save considerable time and labor in positioning the girts. The simplicity of my tool enables the same to be constructed at a very low cost and furthermore the tool will, at all times, be efficient and reliable in carrying out the purposes for which it is designed.

While I have shown the preferred embodiment of my invention, it is to be understood that various changes in the size, shape and arrangement of parts may be resorted to, without departing from the spirit of the invention or the scope of the appended claims.

40 I claim:

1. For use with the spaced uprights of a sectional derrick, and a girt adapted for disposition between said uprights, a tool for positioning the girt in locked engagement with the uprights, said tool comprising a rockable lever, a member extending laterally from one end of the lever for engagement across the top of the girt, means attached to said member for engagement with one end of the girt, and a bearing element connected with said end of the lever.

2. In a jack tool for use with the girts on a derrick structure, a lever, a member extending upwardly from the lower end of the lever for disposition across the top of the girt to force the latter downwardly when the lever is actuated, a hooked bar attached at its inner end to the member for engagement over the adjacent end of the girt, and a finger pivoted at its inner end to the lower end of the lever, the outer end of said finger adapted to engage the adjacent portion of the derrick structure.

3. In a jack tool for positioning the girts on a derrick structure wherein a stud is car-

ried by the derrick structure, an elongated lever, the lower end thereof being curved downwardly, a finger pivoted at its inner end on the curved lower end of the lever, the outer end of the finger being notched for engagement with said stud, a spindle projecting laterally from the lever adjacent the curved lower end thereof for disposition across the top of the girt, and means attached to said spindle for engagement with the end of the girt for moving the adjacent portion of the derrick structure into position for properly receiving said adjacent end of the girt.

4. In a jack tool for positioning the girts on a derrick structure wherein a stud is carried by the derrick structure, an elongated lever, the lower end thereof being curved downwardly, a finger pivoted at its inner end on the curved lower end of the lever, the outer end of the finger being notched for engagement with said stud, a spindle projecting laterally from the lever adjacent the curved lower end thereof for disposition across the top of the girt, and means attached to said spindle for engagement with the end of the girt for moving the adjacent portion of the derrick structure into position for properly receiving said adjacent end of the girt.

5. In a jack tool for use with the spaced uprights of a sectional derrick, and a girt adapted for disposition between said uprights, a member for engagement with one of the uprights, a girt engaging means, and as actuating member operatively connected with the first mentioned member and said means for positioning the girt in locked engagement with the uprights.

In testimony whereof I affix my signature.

HOWARD E. WHITE.
